FIG. 1 is a perspective view of a combined service core and fluorescent lighting system showing our new design; and

FIG. 2 is an enlarged fragmentary view in perspective showing one of the fluorescent fixtures;

FIG. 3 is a bottom plan view on a reduced scale of the combined service core and fluorescent lighting system; and

FIG. 4 is an enlarged fragmentary view in perspective showing a part of the outboard vertical side of an enclosure and an end sleeve.

We claim:

The ornamental design for a combined service core and fluorescent lighting system, as shown and described.
